[57] CLAIM

The ornamental design for a heater front with doors, as shown.

DESCRIPTION

FIG. 1 is a front perspective view of a heater front with doors, showing our new design;

FIG. 2 is a left side elevational view thereof;

FIG. 3 is a rear elevational view thereof;

FIG. 4 is a top plan view thereof;

FIG. 5 is a bottom plan view thereof.

The broken line disclosure of a part of a stove in FIG. 1 is for illustrative purposes only and forms no part of the claimed design.

FIG. 1.

FIG. 5.

FIG. 4.

FIG. 2.

FIG. 3.
